UNITED STATES PATENT OFFICE.

ROBERT B. IRWIN, OF ROCHESTER, NEW YORK.

CAR-DOOR CONSTRUCTION.

1,297,854.

Specification of Letters Patent.

Patented Mar. 18, 1919.

Application filed February 18, 1918. Serial No. 217,887.

To all whom it may concern:

Be it known that I, ROBERT B. IRWIN, a citizen of the United States, residing at Rochester, in the county of Monroe and 5 State of New York, have invented certain new and useful Improvements in Car-Door Constructions, of which the following is a specification.

This invention relates to sliding doors 10 which are particularly adapted for use in railway express or mail cars and its object is to so construct this door that neither ice, snow nor water can interfere with the proper working thereof.

15 With this and other objects in view this invention presents a novel construction comprising a combination and arrangement of parts which will be fully illustrated in the drawing described in the specification and 20 pointed out in the claim at the end thereof.

In the accompanying drawing

Figure 1 is a perspective view of the door looking at it from the inside.

25 Fig. 2 is a perspective view of the door looking at it from the outside.

Fig. 3 is a vertical section through the door and the side of the car on which the door is mounted to slide, the section being taken on the line 3^x—3^x on Fig. 1.

30 Fig. 4 is a vertical section through the side of the car on which the door is mounted to slide, the section being taken on the lines 4^x—4^x of Fig. 2.

Fig. 5 is a detail perspective view of one 35 of the lower corners of the door.

In the several figures of the drawing like reference numerals indicate like parts.

The construction of the doors which are now in use in railway express or mail cars 40 is such that ice, snow or water will quickly interfere with the proper working of the door. For this reason the door construction embodying this invention comprises a sliding door 1 which is suspended at the top by 45 the hangers 2 and 3 from the rail 4 which in turn is supported on the inner side of the car. It will be seen from an inspection of Figs. 3 and 4 that the whole weight of the door rests on the brackets or hangers 2 and 3 which for this purpose are provided 50 with suitable rollers which roll on top of the rail 4 and permit the door to freely slide from one side to the other into its opened or closed position.

55 The lower end of the door 1 projects into

a slot 5 provided in a sill 6 of the car. This slot passes through the whole thickness of the sill as shown in Fig. 3 and the sides thereof are reinforced by a series of cross bars 7, 7 which extend at suitable intervals 60 from one side of the slot to the other.

The door 1 is so suspended by its hangers that the bottom thereof does not come in contact with the cross bars 7, 7 and at no time rests upon them. The slot 5 serves to 65 guide the door from one side to the other into its opened or closed position and keeps it in a straight line movement.

The slot 5 extends only the full length of the opening in the side of the car which is 70 provided for the door and the continuation thereof is formed by a channel 8 which is in line with the slot 5 and is also provided in the sill of the car. A horizontal or slightly angular slot 9 cut into the sill 6 on the outside thereof terminates at the bottom of channel 8 and forms a drain therefor. The slot 9 is closed on the outside by means of the swinging shutter 10 which is mounted on the outside of the sill 6 and is normally 80 held tight against the side of the sill by the locking dog 11.

The fact that the slot 5 is open at the bottom makes it impossible for ice or snow or even dirt to accumulate therein.

85 For this reason the run way formed by the slot 5 is always free from any obstruction and permits the door to freely slide therein. To still further eliminate the possibility of clogging up the run way of the door the 90 lower outside edge thereof is serrated as shown in Fig. 5 and ice or snow which is liable to freeze on the outer side of the slot 5 is scraped off by these serrations when the door is opened or closed. The particles that 95 are scraped off on the inside of the slot drop through it and fall to the ground on the outside of the car.

The end of the door 1 when closed is adapted to project into the vertical groove 100 12 which runs the full height of the car door and terminates in the slot 5 at the bottom, so that the snow or ice which deposits in this groove will also drop down and out through the sill to the outside of the car.

105 The groove 12 if desired may be lined on each side with a suitable lining between which the end of the door 1 is adapted to rest when in its closed position. The groove forms a joint between the side of 110

the car and the door which is made almost water-tight by the linings above referred to.

The channel 8 provided on the inside of the car forms a continuation of the slot 5. This channel has the drain slot 9 provided therein in order to allow the snow or water which may accumulate therein to pass out therefrom so as to keep the channel 8 free from any sediment which may form an 10 obstruction to the door that is adapted to slide therein.

The outside of the slot 9 is normally closed by the shutter 10 which is held against the side of the sill by the locking 15 dog 11. When it is desired to drain the channel 8 as above pointed out the locking dog 11 is turned aside to release the shutter 10 which is then adapted to swing away from the slot 9 and permit the water to 20 pass therethrough to the outside of the car.

Copies of this patent may be obtained for five cents each, by addressing the "Commissioner of Patents, Washington, D. C."

I claim—

The combination of a car having a door opening in the side thereof, a sill provided at the bottom of said car with a slot cut into it below said door opening, said sill 25 having a channel forming a continuation of said slot also cut therein with a horizontal slot leading out of the channel to the outside of said sill, a car door, having a series of triangular grooves cut into the lower end 30 and on the outside thereof, suspended on the inside of said car and projecting into the slot and channel in said sill, the triangular grooves in said door projecting slightly above said sill to keep the slot in said sill 35 partially open when said door is suspended therein.

In testimony whereof I affix my signature.

ROBERT B. IRWIN.
